US00D745871S

(12) **United States Design Patent**
Kim et al.

(10) **Patent No.:** US D745,871 S
(45) **Date of Patent:** ** Dec. 22, 2015

(54) **IMAGING DEVICE**

(71) **Applicant:** Hewlett-Packard Development Company, L.P., Houston, TX (US)
(72) **Inventors:** Yu Ri Kim, Singapore (SG); Chung Chiet Edwin Chin, Singapore (SG); Shanthamallappa Kiran Kattesomanahalli, Singapore (SG); Nick Su, Singapore (SG); Yee Mei Cheng, Singapore (SG); Katherine Weilbacher, Singapore (SG); Qian Tao, Singapore (SG); Tee Kiang Phang, Singapore (SG); Wesley Chia, Singapore (SG)
(73) **Assignee:** HEWLETT-PACKARD DEVELOPMENT COMPANY, L.P., Houston, TX (US)

(**) **Term:** 14 Years

(21) **Appl. No.:** 29/480,993

(22) **Filed:** Jan. 31, 2014

(51) **LOC (10) Cl.** 14-02

(52) **U.S. Cl.**

(57) **CLAIM**

The ornamental design for an “imaging device,” as shown and described.

DESCRIPTION

FIG. 1 is a front right perspective view of an imaging device.

FIG. 2 is a front view of the imaging device of FIG. 1.

FIG. 3 is a rear view of the imaging device of FIG. 1.

FIG. 4 is a left side view of the imaging device of FIG. 1.

FIG. 5 is a right side view of the imaging device of FIG. 1.

FIG. 6 is a top view of the imaging device of FIG. 1.

FIG. 7 is a bottom view of the imaging device of FIG. 1; and,

FIG. 8 is a front left perspective view of the imaging device of FIG. 1.

Broken lines and entirely unshaded portions contained within broken lines are not claimed.

1 Claim, 8 Drawing Sheets
